CLAIM

The ornamental design for a meat grinder with funneled feed chute, as shown and described.

DESCRIPTION

FIG. 1 is a top, front and left side perspective view of funneled feed chute for a meat grinder showing our new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is an additional perspective plan view thereof;

FIG. 9 is a top, front and left side perspective view of an embodiment of the funneled feed chute for meat grinder showing our new design;

FIG. 10 is a front view thereof;

FIG. 11 is a rear view thereof;

FIG. 12 is a right side view thereof;

FIG. 13 is a left side view thereof;

FIG. 14 is a top view thereof;

FIG. 15 is a bottom view thereof; and,

FIG. 16 is an additional perspective plan view thereof. Broken lines illustrate environmental structure. The broken lines in the drawings are included for illustrative purposes only and form no part of the claimed design.
